FINGER RING

John L. Hazelquist, Garden City, Mich., assignor to Traub Manufacturing Company, Detroit, Mich., a corporation of Michigan

Filed June 1, 1962, Ser. No. 70,375

Term of patent 14 years

(Cl. D45—10)

FIGURE 3. FIGURE 4. FIGURE 5.

FIGURE 1 is a perspective view of a finger ring showing my new design;

FIGURE 2 is a top plan view thereof;

FIGURE 3 is a left side elevational view thereof;

FIGURE 4 is a front elevational view thereof; and

FIGURE 5 is a right side elevational view thereof.

The drawing is lined to indicate that the central band on the body of the finger ring is formed of yellow metal while the remaining portions are formed of white metal.

I claim:

The ornamental design for a finger ring, substantially as shown and described.
